(57) **CLAIM**

The ornamental design for a tension meter, as shown and described.

DESCRIPTION

FIG. 1 is a front elevational view of a tension meter embodying our new design;

FIG. 2 is a rear elevational view thereof;

FIG. 3 is a right side elevational view thereof, the left side elevational view being a mirror image;

FIG. 4 is a top plan view thereof, the bottom plan view being a mirror image;

FIG. 5 is a front, left side and top perspective view thereof;

FIG. 6 is a rear, right side and bottom perspective view thereof; and,

FIG. 7 is a front elevational view like FIG. 1, showing a transparent part.

The end pieces shown in dotted lines are provided for understanding of the design and form no part of the claimed design.
